DESIGN FOR A BOX FOR ARTISTS' BRUSHES AND PIGMENTS

Herbert Deckinger, New York, N. Y.

Application August 19, 1947, Serial No. 140,946

Term of patent 7 years

(Cl. D74—1)

To all whom it may concern:

Be it known that I, Herbert Deckinger, a citizen of the United States, residing at the city, county, and State of New York, have invented a new, original, and ornamental Design for a Box for Artists' Brushes and Pigments, of which the following is a specification, reference being had to the accompanying drawing, forming part thereof.

Figure 1 is a top view in closed position showing a box for artists' brushes and pigments, showing my new design.

I claim:

The ornamental design for a box for artists' brushes and pigments, as shown.

HERBERT DECKINGER.
